UNITED STATES PATENT OFFICE.

WILLIAM S. HAMM, OF HUBBARD WOODS, ILLINOIS, ASSIGNOR TO THE ADAMS & WEST-LAKE COMPANY, OF CHICAGO, ILLINOIS, A CORPORATION OF ILLINOIS.

DESIGN FOR A FRONT FOR BERTH-LAMPS.

44,564.

Specification for Design.

Patented Aug. 26, 1913.

Application filed June 19, 1913. Serial No. 774,695. Term of patent 14 years.

To all whom it may concern:

Be it known that I, WILLIAM S. HAMM, a citizen of the United States, residing at Hubbard Woods, county of Cook, and State of Illinois, have invented a new, original, and ornamental Design for a Front for Berth-Lamps, of which the following is a specification, reference being had to the accompanying drawing, forming a part thereof, and in which—

Figure 1 is a front elevation of the lamp front; and Fig. 2 is a side elevation thereof.

I claim:

The ornamental design for a front for berth lamp, as shown.

WILLIAM S. HAMM.
